AERIAL TOY

Application filed February 23, 1932. Serial No. 594,503.

This invention relates to an aerial toy and more particularly to a joker's novelty in the form of an aerial toy shaped to simulate a butterfly which is adapted to be self-projected into the surrounding atmosphere by the opening of an envelope-like device or folder in which the toy has been previously disposed after the same has been properly wound up.

10 An object of this invention is to provide an aerial toy of the above mentioned characteristics with a frame of such thinness and lightness as to materially facilitate the flight or projection of the device in the atmosphere and which frame is yet sufficiently rigid as to resist distortion when the toy is in use.

15 Another object of the invention is to materially lighten as well as to augment the rigidity of the parts of an aerial toy of the above mentioned characteristics.

20 In accordance with the general features of this invention there is provided in combination a folder and an aerial toy adapted to be disposed therein after the toy has been wound up and in a position ready to be self-projected into the air the toy including a relatively flat triangular frame made from thin and light sheet material which frame is disposed substantially centrally of the toy 25 and has connected to it wing means with a propeller element at one end of the triangular frame connected to the frame by rubber band means arranged to be wound by the turning of the element to store up energy 30 for subsequently rotating the element when the toy is put into use by the opening of the folder whereby the toy is self-projected out of the folder into the surrounding air or atmosphere.

35 40 Another feature of the invention relates to the detailed construction of the frame of the toy which enables the frame to be made of extremely light material such as aluminum sheet and yet at the same time provides the frame with sufficient rigidity to withstand pressure and distortion incident to the winding of the rubber band means connected to the propeller-like element.

45 Other objects and features of this invention will more fully appear from the follow-

ing detailed description taken in connection with the accompanying drawings which illustrate a single embodiment of the aerial toy and in which

50 Figure 1 is an end view of one type of folder having an aerial toy of my invention disposed therein;

55 Figure 2 is an end view of another type of folder having an aerial toy of my invention disposed therein;

60 Figure 3 is a plan view of the aerial toy;

Figure 4 is a bottom view of the aerial toy;

65 Figure 5 is a longitudinal cross sectional view taken on the line V—V of Figure 3 looking in the direction indicated by the arrows and drawn to an enlarged scale; and

70 Figure 6 is a transverse enlarged cross sectional view taken through the frame of the toy on the line VI—VI of Figure 4 looking in the direction indicated by the arrows in the drawings.

75 The reference character 10 designates generally an aerial toy embodying the features of this invention which toy is adapted to be disposed in a folder or envelope device such as the two ply folder 11 shown in Figure 1 or in an envelope-like device such as the three ply folder 12 shown in Figure 2. This invention is not concerned with the details of the envelope-like device or folder in which 80 the toy is disposed inasmuch as any suitable envelope device may be used to enclose the toy in the position ready to be projected or released into the surrounding atmosphere by the opening of the envelope-like device. In 85 other words this invention does not relate per se to the folder but rather relates to the combination of the folder or envelope-like device with an aerial toy of my invention and still more specifically the invention pertains to the construction of the aerial toy itself.

90 95 The aerial toy of my invention is illustrated in detail in Figures 3, 4, 5, and 6. In general it includes a triangular frame 15 disposed substantially centrally of and connected to wing means 16 and having connected to one end thereof a propeller-like element 17. The wing means and the propeller-like element as will be evident from 100

Figures 3 and 4 are shaped to cause the toy to simulate a butterfly. Of course it will be appreciated that these elements of the toy may be shaped to simulate other flying creatures or things without deviating from the spirit of the invention, especially since the invention relates primarily to the construction of the frame 15 so as to enable it to be made of exceedingly light material and yet have sufficient rigidity to withstand pressure thereon and distortion thereof incident to the operation and use of the toy. Also it might be noted at this time that the wing means 16 is reinforced by a curved wire strand 18 disposed between the wing means and the frame 15 and having its ends anchored to the wing means by means of adhesive tabs 19 disposed over the ends of the strand 18 and glued to the wing means proper. The wing means may be made of any suitable material such for example as paper sheet and is preferably glued to the top of the triangular frame 15 so as to be permanently secured thereto. Furthermore as will be noted from Figures 3 and 4 the wing means 16 and the propeller-like device 17 may be provided with suitable ornamentalations to cause these elements as previously noted to give the toy a butterfly appearance. The frame 15 may be blanked out from any suitable sheet material such for example as metallic sheet, fibrous sheet, phenolic condensation material sheet and the like. The material used however should be as light and thin as is feasible so as to enable the toy to have the desired lightness necessary for its propulsion through the air. I have found that good results may be obtained by making this frame of thin aluminum sheet which material is not only light but is quite workable. The frame may be blanked from such sheet material by any suitable equipment such for example as a punch or kicker press. Further by making the frame in accordance with the features of this invention I find that I can use material which is so thin and light that without some reinforcing or strengthening means the frame would buckle or distort when subjected to any pressure such as is imposed on it by the winding of the propeller-like element. Therefore in order to prevent such buckling or distortion of the frame and yet enable it to have a minimum weight I reinforce this frame by ribbing or corrugating it at the same time as the frame is blanked out of the sheet material. This ribbing or corrugation is clearly shown in Figures 4 and 6 and is designated by the reference numeral 20. Moreover this ribbing 20 extends around the entire frame so that the frame is strengthened both transversely and longitudinally. Of course it is evident that by providing the base end of the triangular frame with ribbing as well as the

sides of the frame with ribbing transverse distortion of the frame is prevented and longitudinal distortion of the frame at the base of the triangular frame is also prevented.

The base end of the triangular frame or in other words the widest portion of the frame has formed integral with it a lateral or downwardly extending apertured ear 21 through the hole of which extends a wire shaft 22 anchored at its outer end to the propeller-like element 17 (Figure 6). Surrounding this wire shaft 22 and disposed between the ear 21 and the propeller-like element 17 are a plurality of glass beads 23 which serve to space the propeller element from the end of the frame and to prevent binding of that element on the frame and interference with the free rotation of the element after it has been wound.

The innermost end of the wire shaft 22 is turned back upon itself at 24 to form an eye adapted to receive one end of the rubber band means 25 the other end of which is looped over a tang 26 punched out from the body of the frame proper. This tang 26 is downwardly offset relative to the frame. It however is not laterally offset to such an extent as to materially interfere with the flat characteristics of the frame so that the toy including the frame may be disposed in a relatively flat position within a folder such as either one of the folders 11 or 12.

Furthermore one or more rubber bands may be used to comprise the rubber band means 25 depending upon the strength of the frame and the amount of force desired to rotate the propeller device 17. I have attained excellent results by using two small rubber bands as shown in the drawings.

In the use of the device the propeller-like element 17 is rotated to wind the rubber band means 25 and this may be accomplished by turning the element 17 fifty or sixty times. Thereafter the device is laid in a substantially flat position within the enclosing envelope or folder ready for use. The folder may be disposed in another envelope or it may be used as a place card on a dinner table in which event the folder may be held shut by placing something on it such for example as a spoon, fork or napkin.

It will of course be appreciated that as soon as the folder is caused to be opened the wound up propeller element 17 projects the aerial toy bodily into the surrounding atmosphere much to the surprise of the person opening the folder.

I have found from my experience in marketing and selling devices of the present character that they have met with much success as a joker's novelty. They may be sent through the mail or they may be used as place cards at dinner parties but in either event they perform substantially the same and much to the surprise of the recipient.

Now it is of course to be understood that although I have illustrated and described in detail the preferred embodiment of the invention the invention is not to be thus limited but only insofar as defined by the scope and spirit of the appended claim.

I claim as my invention:

As an article of manufacture, an aerial toy including a frame, wing means connected thereto with said frame substantially centrally thereof, a propeller-like element at one end of said frame, and means connected to said frame arranged to be wound by the turning of said element, said frame being made of such thin sheet material as to require a depressed portion in the same to give it sufficient rigidity to resist distortion when in use in the toy and being triangular in shape with the legs of the triangle reenforced by longitudinal ribs formed therein.

In testimony whereof I have hereunto subscribed my name at Asbury Park, Monmouth County, New Jersey.
